(57) **CLAIM**

The ornamental design for locking pliers with toolset pocket, as shown and described.

DESCRIPTION

FIG. 1 is a perspective view of an embodiment of the locking pliers with toolset pocket;

FIG. 2 is a top view of the embodiment of FIG. 1;

FIG. 3 is a bottom view of the embodiment of FIG. 1;

FIG. 4 is a side view of the embodiment of FIG. 1;

FIG. 5 is a side view of the embodiment of FIG. 1;

FIG. 6 is a rear view of the embodiment of FIG. 1; and,

FIG. 7 is a front view of the embodiment of FIG. 1.
